UNITED STATES PATENT OFFICE.

WILLIAM A. IRWIN, OF NEW YORK, N. Y., AND LEO FREDERICK JACKSON, OF TAUNTON, MASSACHUSETTS.

AUTOMOBILE-LAMP.

1,328,153.

Specification of Letters Patent. Patented Jan. 13, 1920.

Application filed June 11, 1919. Serial No. 303,311.

To all whom it may concern:

Be it known that we, WILLIAM A. IRWIN and LEO F. JACKSON, citizens of the United States, and residents, respectively, of the city of New York, borough of Manhattan, in the county and State of New York, and Taunton, in the county of Bristol and State of Massachusetts, have invented a new and Improved Automobile-Lamp, of which the following is a full, clear, and exact description.

This invention relates to vehicle lamps and has particular reference to headlights for motor vehicles or the like.

15 Among the objects of the invention is to provide a lamp designed for the purpose of throwing ample light on the roadway ahead without any possibility of glare.

Another object is to provide a lamp casing 20 having means for diffusing the light upward and laterally in all directions so as to illuminate the roadway at the sides of the vehicle as well as surrounding objects.

By the provision of means such as set 25 forth herein or their equivalent the danger or likelihood of accidents or interference along the street or roadway so commonly incident to imperfect illumination may be largely avoided.

30 With the foregoing and other objects in view the invention consists in the arrangement and combination of parts hereinafter described and claimed, and while the invention is not restricted to the exact details 35 of construction disclosed or suggested herein, still for the purpose of illustrating a practical embodiment thereof reference is had to the accompanying drawings, in which like reference characters designate the same 40 parts in the several views, and in which—

Figure 1 is a side elevation showing my improvement attached to a standard vehicle lamp, parts being broken away.

Fig. 2 is a front elevation of the same.

45 Fig. 3 is a vertical transverse section on the line 3—3 of Fig. 1.

Fig. 4 is a sectional detail on the line 4—4 of Fig. 2.

Fig. 5 is a detail of the extension base for 50 the lamp bulb.

Fig. 6 is a vertical transverse section similar to Fig. 3, but showing a modified structure.

Fig. 7 is a detail of one of the ribs for 55 holding the sectional cylinder.

Fig. 8 is a sectional detail corresponding to the lower left hand portion of Fig. 1, but showing a modified construction; and

Fig. 9 is a detail perspective view of one of the clips as illustrated in Fig. 8. 60

Referring now more specifically to the drawings we show a lamp comprising a casing including an extension hood and a transparent wall structure, and a lamp bulb or its equivalent located within the casing in 65 such a manner as to throw its light directly outward laterally as well as forward. As indicated in the drawings we provide a means for carrying out our improvement in a practical manner using as a basis a lamp 70 casing 10 which may be of any standard design or size and including a reflector 11, a lens or window 12, and a lens holding rim 13.

Ordinarily the lamp bulb 14 is located 75 within or back of the lens 12, but in our improvement we provide a central hole 12' in the lens and extend the lamp bulb so as to bring it beyond or in front of the lens 12. To effect this result we employ an extension base 15 of any suitable character 80 for the bulb, but we have found the means illustrated in Fig. 5 to be suitable for this purpose, the same embodying a plurality of 85 interchangeable coupling sections, each section carrying a plurality of conductors 16, the conductors of each section being adapted to make contact with the conductors of the next adjacent sections. The lamp bulb obviously is attachable to the outermost section irrespective of the number of sections 90 employed. Obviously in place of the built-up base as illustrated a single or integral base may be made in the form of a special lamp if desired, depending upon the design 95 of the original or main supporting lamp casing.

17 indicates a hood structure comprising a collar 18 preferably of annular form and having an outwardly flared front edge, a 100 rim 19, the rear end of which is bent inward forming a curved lip, and a dimmer lens 20 gripped between the rear edge of the collar and the innermost edge of the lip of the rim 19. These parts may be secured firmly 105 together by any suitable means, but we prefer the means indicated in Figs. 1 and 4 and comprising a plurality of angular clips 21 carried by the collar and bearing rearward against the outer face of the dimmer 110

lens 20 where they are held firmly by means of clamping bolts 22, or their equivalent, passing radially of the collar through the overlapping portions of the collar and rim 19 as well as through the parallel portions of the clips 21.

The hood 17, made up as indicated above, is carried sufficiently far in advance of the main lamp casing 10 to afford a clear space 10 between the lamp casing and the hood through which the light from the lamp bulb 14 is adapted to be diffused laterally without material obstruction to illuminate the vehicle as well as the roadway. In order 15 to support the hood in its forward spaced relation to the casing 10 we employ a plurality of ribs 23 made preferably of metal and having angularly disposed ends 24, the intermediate portions of the ribs being carried 20 inward toward the inner margins of the rims 18 and 19. Any suitable number of these ribs may be employed such number, however, including two lying diametrically opposite each other and on the same level. 25 The angularly shaped ends 24 of the ribs are connected to the hood and to the rim 18 by screws, bolts or the like indicated at 25 and 26 respectively with the exception that the aforesaid two ribs that are on the same level 30 are connected to the hood by means of a rod 27 which projects entirely across the hood and beyond the side portions thereof to a distance great enough to accommodate hoods of various sizes, designs or dimensions. Upon this diametrically arranged rod 27 is supported a reflector 28 shown in the form of a flat panel with a mirrored inner surface 29, the outer portion of the reflector being opaque so as to serve as a 35 positive dimmer preventing the glare of the light from being cast too high along the roadway. The ends of the rod 27 after adjustment to the proper size of hood may be clipped off if they are too long so that when 40 the nuts 30 are applied to the ends a neat construction is provided. The nuts 30 provide means for not only securing the adjacent portions of the hood together to the horizontal ribs 23, but also serve to lock 45 the reflector 28 at any desired elevation or angle according to the type of lamp and the local requirements as to the projection of the light. The ribs 23 obviously may be 50 made of any necessary strength or rigidity 55 to constitute a satisfactory support for the lamp hood.

The dimmer lens 20 is peculiarly constructed so as to have upper and lower spaced translucent segments or zones 20^a and 20^b respectively. The upper segment 20^a covers substantially half of the area of the lens while the lower segment 20^b covers practically only about one half of the lower area, leaving a horizontal zone or segment 60 20^c between the horizontal diameter of the

lens and the upper edge of the lower translucent zone 20^b perfectly clear so as to transmit a considerable portion of the light direct from the bulb and the interior of the lamp casing so as to illuminate the roadway ahead either directly or as a reflection against the mirrored surface of the reflector 28. It will be apparent that it is impossible for any intense light or glare to proceed forward through the lens 20 because of the 70 tinted or otherwise modified portions 20^a and 20^b thereof and the dimmer reflector 28 carried in advance of the clear portion. Any suitable means may be provided to fill the gap between the standard lamp casing and 75 the hood 17 in connection with the ribs 23. This means in Figs. 1, 2 and 3 comprises a hollow transparent cylinder or shell 31 the same being shown as an unbroken cylindrical shell and extending forward from the 80 standard lens 12 to approximately contact with the dimmer lens 20 and held in place from lateral movement by means of set screws 32 tapped through the ribs 23 and locked in place by means of lock nuts 33. 85 This shell is made preferably of transparent glass or its equivalent so that light may proceed laterally therethrough from the bulb 14 for the purposes already set forth. 90

Figs. 6 and 7 show a variation in rib 95 structure and coöperating shell structure. In other words the shell is made of a plurality of cylindrical shell segments 31' shown as four in number and held in place by channel formation of ribs 23'. In other 100 words the main portion of each rib is of double channel or T-form in cross section whereby there are provided on opposite sides of each rib grooves 23^a into which the longitudinal edge portions of the segments 105 31' are supported. The ribs are secured in place by means similar to the means already described in connection with the first set of figures, and the ribs serve the same purposes so far as the hood and dimmer means are 110 concerned as the ribs 23.

Referring now to Figs. 8 and 9 we wish to point out that we may use a series of fingers 34 bent to conform to the outer peripheral portion of the casing 10 and lying 115 over the cylindrical flange portion 10' thereof and to which the angular ends 24 of the hood carrying ribs may be secured by means of bolts or the like 26'. The outer ends of the finger portions are bent inward at 36' 120 forming interlocking means preventing any possibility of rotation of the fingers around the axes of the bolts 26' which pass through holes 34'. Thus our attachment may be applied to standard lamp casings without any 125 alteration of such standard lamp casings, except the boring of a few simple holes.

We claim:

1. The combination with a lamp casing and a source of light therein, of a hood 130

comprising a collar and light modifying means within the collar serving to dim the beam of light cast forward from the lamp casing, a series of substantially parallel ribs having their ends fixed to the lamp casing and the hood whereby the hood is held in forward spaced relation to the lamp casing, and cylindrical transparent shell means extending between the casing and the hood 10 and within the ribs.

5 serving as a dimming device in advance of the casing and in the beam of light projected forward therefrom, means extending 15 between the casing and the hood and spanning the space between them serving to fix the hood in rigid position, and transparent shell means filling the space between the casing and the hood and serving to allow 20 free emission of light laterally through the space between the casing and the hood.

2. The combination with a lamp casing and a source of light therein, of a hood

WILLIAM A. IRWIN
LEO FREDERICK JACKSON
